UNITED STATES PATENT OFFICE.

FRED E. KLING, OF YOUNGSTOWN, OHIO.

HOT-BLAST STOVE.

Application filed May 15, 1926. Serial No. 109,452.

This invention relates to hot blast stoves and more particularly to continuous hot blast stoves, and has for one of its objects the provision of a continuous hot blast stove having a materially higher efficiency than hot blast stoves heretofore constructed.

Another object is to provide a stove of the class described which will have a long life due to its novel construction.

10 A further object is to provide a stove having novel means for permitting expansion of the parts due to the high temperatures.

A still further object is to provide a stove having the novel construction, design and 15 combination of parts hereinafter described and illustrated in the accompanying drawings.

In the drawings:

Figure 1 is a vertical section through a 20 stove constructed in accordance with this invention.

Figure 2 is a sectional plan of the stove.

Figure 3 is a vertical section on the line III—III of Figure 1.

25 Referring more particularly to the drawings, the numeral 2 designates the stove as a whole, which is composed of a combustion chamber 3 and a heat exchanging chamber 4. A gas or other fuel burner 5 is mounted in 30 the end wall 5^a of the stove and enters the combustion chamber 3. The burner 5 is preferably a gas burner adapted to burn dry cleaned blast furnace gas.

The combustion chamber 3 opens into the 35 heat exchanging chamber 4, which last named chamber is provided with a flue or stack opening 4^a at the opposite end from the combustion chamber so that the products of combustion must flow through the heat exchanging chamber in order to pass to the stack.

A system of air blast pipes 6 are mounted in the heat exchanging chamber 4. The pipes 6 enter the chamber 4 at its end farthest 45 from the combustion chamber 3 and are coiled upwardly and downwardly through the chamber 4 and exit through the opposite end of the heat exchanging chamber above the combustion chamber. The several coils 50 of the pipes 6 are inclined slightly from the vertical so as to form supports for baffle walls 7 which are arranged in front of each of the coils of pipe and rest on the pipe. The inclination of the coils of pipes 6 is as 55 slight as practical in order to support the baffle walls and at the same time reduce the

bending strains in the pipes to a minimum. An additional baffle wall 7^a is arranged under the exit end of the pipes 6 to prevent the products of combustion impinging directly against the pipes as they leave the combustion chamber.

The cold blast is adapted to enter the pipes 6 from a main 8 through a manifold 9 and to flow through said pipes counter-current to the products of combustion from the combustion chamber 3 and to exit from the pipes 6 through a manifold 10 into a hot blast main 11.

The several coils of the pipes 6 are of considerable length and also the pipes increase in diameter from the entering to the exit end, as for instance, the entering end of the pipes may be four inches in diameter while the exit end will be six inches or more in 75 diameter, and the intermediate portion will be five inches in diameter, so as to accommodate for the expansion of the air as it becomes heated.

The length and varying diameters of the 80 pipes 6 necessitates the use of a plurality of pipe sections to make up each pipe and each of these sections will be preferably welded to the preceding section so as to make a tight joint.

By passing the blast air through the pipes 6 counter-current to the products of combustion passing through the chamber 4, the products of combustion contact with the portion of the pipes 6 containing the low temperature air, resulting in high efficiency of utilization of heat and consequently low consumption of gas or fuel.

The portion of the pipes 6 in the hot zone 95 of the stove that is nearest the combustion chamber 3 is preferably made of a chrome steel alloy so as to withstand the high temperatures to which they are subjected without progressive oxidation, while the remainder of the pipes 6 located in the cooler 100 zone of the stove that is farthest from the combustion chamber 3 may be composed of ordinary standard or commercial steel.

The pipes 6, due to the temperatures to which they are subjected, will have considerable expansion. Therefore, the coils of the pipes 6 are terminated short of the top wall of the chamber 4 so as to permit them to expand upwardly, while the lower ends of the coils are supported or seated on the bottom 110 wall of the chamber.

The upper ends of the coils of pipes 6 are

each provided with guide rods 14 which project upwardly into suitable recesses 15 in the top wall of the stove to support the upper ends of the coils and permit free expansion thereof.

The pipes 6 in the hot zone or nearest the combustion chamber 3 will be subjected to the highest temperatures and will, therefore, have the greatest expansion, whereby the 10 coils nearest the combustion chamber will tend to lift the adjoining coils from the bottom wall of the stove while the coils nearest the combustion chamber remain seated on the bottom wall. To compensate for this 15 unequal expansion, and to prevent undue load or stresses on the pipes due to the unequal expansion, the coils of the pipes 6 in the cooler zone, or farthest from the combustion chamber 3, are provided with plunger 20 rods 16 which extend downwardly into a recess 17 and are engaged by springs 18 which serve to normally force the cool pipe coils, and thereby prevent warping of the pipe coils due to unequal expansion.

25 The temperature of the air blast in stoves of this class can be automatically controlled by standard thermostat gas control apparatus operable by the temperature of the hot blast and adapted to regulate the flow of gas 30 to the burner 5. The thermostat mechanism is not shown, since any of the several standard thermostatically controlled regulators may be used.

35 The efficiency of a hot blast stove of this class is materially higher than stoves heretofore in use, since the temperature of the waste gases or products of combustion leaving the heat exchanging chamber can be kept at approximately five hundred degrees Fahrenheit, due to the waste gases being in contact with the pipes 6 carrying air at approximately two hundred degrees Fahrenheit prior to their exit to the stack. The 40 efficiency of this stove will also be higher due to its materially decreased radiating surface over stoves heretofore in use.

45 The present stove will require considerably less labor due to it being capable of automatic control, and due to the fact the chimney and other valves are eliminated thereby reducing the parts liable to give trouble.

50 The present stove will not clog with dust since the dust can be blown off the pipes 6 with soot-blowers during the operation of the stove, thereby permitting constant high efficiency.

55 The above and many other advantages will be readily apparent to those skilled in the art.

60 While I have shown and described one specific embodiment of my invention, it will be understood that I do not wish to be limited thereto since various modifications may be 65 made without departing from the scope of

my invention as defined in the appended claims.

I claim:

1. A continuous hot blast stove comprising a combustion chamber, and a heat exchanging chamber through which the products of combustion pass from said combustion chamber, a plurality of metallic pipes coiled upwardly and downwardly through said heat exchanging chamber, the coils of said pipes 70 being inclined slightly from the vertical, baffle walls along each of said coils of pipes, said baffle walls being alternately spaced from the bottom and top walls of said heat exchanging chamber to cause the products of combustion to travel along all of said pipes, means for permitting said coils of pipe to expand upwardly, and means for compensating for the greater expansion of the pipes closest to said combustion chamber over the pipes farthest from said combustion chamber.

2. A continuous hot blast stove comprising a combustion chamber, and a heat exchanging chamber through which the products of combustion pass from said combustion chamber, a plurality of metallic pipes coiled upwardly and downwardly through said heat exchanging chamber, the coils of said pipes being inclined slightly from the vertical, baffle walls along each of said coils 90 of pipes, said baffle walls being alternately spaced from the bottom and top walls of said heat exchanging chamber to cause the products of combustion to travel along all of said pipes, and means for permitting said 95 coils of pipe to expand upwardly.

3. In a hot blast stove having a heat exchanging chamber, a plurality of air blast pipes coiled upwardly and downwardly through said chamber, said coils of said pipes terminating short of the top wall of said chamber, and guide rods on the upper ends of said coils of pipe and mounted in recesses in the top wall of said chamber so as to support said coils and permit expansion of 105 said pipe.

4. In a hot blast stove having a heat exchanging chamber, a combustion chamber communicating with the heat exchanging chamber at one end thereof and a flue communicating with said heat exchanging chamber at the other end thereof so that the products of combustion will pass from said combustion chamber through said heat exchanging chamber from end to end thereof, a plurality of air blast pipes coiled upwardly and downwardly through said heat exchanging chamber, said coils of pipes terminating short of the top wall of said heat exchanging chamber, guide rods projecting from the upper ends of said coils of pipe and extending into recesses in the top wall of said heat exchanging chamber, said coils of pipes adjacent said combustion chamber being adapted to have a greater expansion than the pipe 115 120 125 130

coils farther from said combustion chamber due to the greater heat of the products of combustion whereby said coils of pipes having the least expansion will be lifted
5 from their seats, and spring supports for supporting the lower ends of the coils of pipes having the lesser expansion adapted to

balance the weight of said cooler coils and thereby compensate for the unequal expansion and prevent breakage of said pipes. 10

In testimony whereof, I have hereunto signed my name.

FRED E. KLING.
